SIDING MATERIAL

Walter H. Davis, Shreveport, La.

Application November 18, 1944, Serial No. 564,066

4 Claims. (Cl. 20—5)

My invention relates broadly to coverings for wall surfaces, but more particularly to house siding material employed as the finishing surface on the exterior walls of residences and other buildings.

An object of my invention is to provide units of siding material that may be applied to a wall surface with inexperienced labor.

Another object of my invention is to provide units of siding material carrying masonry design patterns and fashioned to be overlapped in the installation to modify the designs of the separate unit and to produce various composite masonry designs.

Another object of my invention is to provide units of siding material that are adapted to be overlapped in being installed, with border lines simulating mortar joints so that the overlapping edge of one unit of the siding on another unit of siding will appear to an observer as a mortar line in the covered wall.

Other objects and advantages of my invention will appear from a reading of my detailed description to follow of forms of siding that embody my invention.

My siding material should preferably be made in a pliable form in a similar manner to composition roofing material and preferably more pliable since, as shown later in this specification, it is adapted for covering raised portions of a wall surface such as window frames and door frames and is adapted to be bent around corners of buildings and in some applications it must be bent back on itself.

The exterior surface of my siding material should be embossed in designs of stones, tiles or the like bordered with mortar joints. Such designs may be smooth painted surfaces, or they may be made granulated in accordance with prior art teachings relating to the making of composition roofing material and siding material.

For the purpose of illustrating my invention, I show in my drawing only patterns of blocks of stone bordered with mortar joints, but it is to be understood that tiles or other building wall materials might be shown in place of the stones within the scope of my invention.

In the drawing:

Figure 1 is a plan view of a single stone unit of siding material embodying my invention.

Figure 2 is an elevation view illustrating the application of the single unit of siding material on the outside walls of houses.

Figure 3 is a cross section view taken on line 1—1 of Figure 2.

Figure 4 is a lay-out view illustrating the mode of application of a single stone siding unit to wall surfaces.

Figure 5 is a plan view of a multiple stone siding unit embodying my invention and,

Figure 6 is a lay-out view illustrating the application of the multiple stone unit illustrated by Figure 5 on a wall surface.

In the drawing referring to Figures 1, 2, 3, and 4, numeral 1 designates the single stone siding unit as a whole. Numeral 2 designates the building stone and numeral 3 designates the mortar line surrounding the building stone 2. The mortar line 3 extends to the edge and around the entire circumference of the building unit 1. The building unit 1 is made out of pliable matter to adapt it to be laid on the raised portions of a wall surface and around the corners. The building units 1 may be overlapped in various manners to create a composite pattern of dissimilar stones all of which are separated by mortar lines. When the building units 1 are laid in overlapping manners such as shown in the drawing of a house in Figure 2, patterns of stone are produced to simulate actual stone type wall constructions. The reader will appreciate that the finished patterns will all differ from one another. This is not possible in the use of prior art stone type siding materials that are not designed to be overlapped except along their bordering edges.

To cover the wall boards B of the house H with siding units 1, as best illustrated by Figure 4 of the drawing, the workman merely nails them on with siding nails 4, in any manner he sees fit to do so, to produce the desired patterns of stone work. The only care that he must take is to see that the units 1 overlap one another both as to vertical directions and horizontal directions. No matter how much or how little the units 1 are overlapped, mortar lines 3 will show up between the stones 2.

The reader will see in Figure 4 that the flat stones 2 constituting the bottom layer of the pattern are made out of the same size units as are the thicker stones 2 above them. The reader will also notice that the width of the various stones 2 is modified by the degree of overlapping of the siding units 1.

In applying my siding units 1 to a window frame W or a door frame D, as best shown in Figure 3 of the drawing, the siding unit 1 is first nailed down directly to the door frame D and is then bent back on itself and extended to the wall board B where it is overlapped by a second siding unit 1. The two overlapping siding units 1 are

nailed to the wall board B with other siding nails 4. The siding nails 4 should preferably be nailed in the mortar line 4. Heads of the siding nails 4 should preferably be of the same color as the mortar lines 3 to prevent them from showing up to the eyes of an observer. It is to be understood that if desired the siding units 1 may be glued to the wall boards B or other surfaces to which they are applied within the scope of my invention.

The covered door frame D takes on the appearance of projecting stones bordering the door opening. This application of my siding material simulates the common practice in real stone work. The application of my siding material to the door frame D and other frame openings, such as the window frame W, saves the cost of painting the frames, the cost of which would greatly exceed the cost of covering them with my siding material. The reader should also keep in mind that in addition to saving the cost of the original paint job, the use of my siding material saves also the cost of repainting these frame surfaces.

The modified form of multiple stone building unit 5 illustrated in my drawing in Figure 5 and Figure 6 is designed to be applied to wall boards B or on door frames D or window frames W with siding nails 4 in the same manner as described above in connection with the single stone unit 1.

In Figure 6 of the drawing the reader will see wherein the height of the stones 6 of the multiple stone unit 5 is varied by the degree of vertical overlapping of the multiple stone units 5 as applied to the wall boards B. Variation in the width of the end stones 6 is brought about by variations in the horizontal overlapping of the end stones 6 of the multiple stone units 5. The width of the center stone 6 is not varied in the normal mode of application of the multiple stone units 5 to wall boards B. As in the case of the single stone siding unit 1, when overlapping, the multiple stone units 5 produce an arbitrary stone pattern showing all of the stones 6 completely surrounded by mortar lines 7.

Having thus described my invention, I claim:

1. A siding unit adapted to be fastened to a wall surface or the like in overlapping relationship with similar siding units comprising a flex-

ible base member and a covering applied to the exposed surface of said base member, said covering simulating a pattern of masonry construction, said covering being extended to the extreme edge portion of said base member throughout the entire length of the perimeter of said base member, whereby a variety of complete masonry patterns may be fashioned by varying the amount of overlap of said siding unit with one or more similar siding units.

2. A siding unit adapted to be fastened to a wall surface or the like in overlapping relationship with similar siding units comprising a thin, flat base member and a covering on the exposed side of said base member, said covering simulating a pattern of masonry construction including mortar lines, said pattern being extended to the extreme edge portion of said base member throughout the entire length of the perimeter of said base member whereby a variety of complete composite masonry patterns including mortar lines may be fashioned by varying the amount of overlap of said siding unit with one or more similar siding units.

25 3. The siding unit as claimed in claim 2 wherein in said pattern consists in a single stone surrounded by mortar lines.

4. A siding unit adapted to be fastened to a wall surface or the like in overlapping relationship with similar siding units comprising a thin, 30 flat, flexible base member and a covering on the exposed side of said base member, said covering simulating a pattern of masonry construction including mortar lines surrounding stones, 35 tiles or the like and wherein the perimeter of said pattern is completely bordered by a mortar line and wherein said mortar line is extended to the extreme edge of said base member throughout the entire perimeter of said base member, whereby 40 by a variety of complete, arbitrary, composite masonry patterns completely bordered by mortar lines and including mortar lines surrounding all of the stones, tiles or the like in said pattern may be fashioned by overlapping said siding unit in various amounts with one or more similar siding units.

45 WALTER H. DAVIS.
